DESIGN FOR A REGULATOR

Herman W. Carnes, Indianapolis, Ind., assignor
to Oxweld Acetylene Company, a corporation
of West Virginia

Application May 12, 1939, Serial No. 84,938

Term of patent 14 years

To all whom it may concern:

Be it known that I, Herman W. Carnes, a citizen
of the United States, residing at Indianapolis,
in the county of Marion and State of
Indiana, have invented a new, original, and
ornamental Design for a Regulator, of which the
following is a specification, reference being had
to the accompanying drawing forming a part
thereof in which—

Fig. 1 is a front elevational view of a regulator showing my design;

Fig. 2 is a side elevational view; and

Fig. 3 is a rear elevational view of the regulator shown in Fig. 1.

I claim:

The ornamental design for a regulator, substantially as shown.

HERMAN W. CARNES.
